CLAIM

The ornamental design for a golf push cart, as shown and described.

DESCRIPTION

FIG. 1 is a front, right and top perspective view of a golf push cart, showing my new design;
FIG. 2 is a rear, left and bottom perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof;
FIG. 9 is an enlarged view of portion 9 of FIG. 1 thereof, and,
FIG. 10 is an enlarged view of portion 10 of FIG. 2 thereof. The dot-dash broken lines depict the boundaries of the enlargements, and form no part of the claimed design.

1 Claim, 10 Drawing Sheets
